UNITED STATES PATENT OFFICE.

JOHN HAYS HAMMOND, JR., OF GLOUCESTER, MASSACHUSETTS.

MULTIPLEX RADIO TELEPHONY AND TELEGRAPHY.

Application filed May 13, 1912, Serial No. 696,899. Renewed December 11, 1918. Serial No. 266,362.

To all whom it may concern:

Be it known that I, JOHN HAYS HAMMOND, Jr., a citizen of the United States, residing at Gloucester, in the State of Massachusetts, have invented certain new and useful Improvements in Multiplex Radio Telephony and Telegraphy, of which the following is a specification.

My invention relates to systems for the simultaneous transmission and reception of a plurality of telephone and telegraph messages by means of radiant energy, and relates more particularly to systems in which selectivity is secured by employing distinctive wave lengths and wave-group frequencies or periodic amplitude variations. In such systems I secure a still higher degree of selectivity by using a combination of high-frequency waves and at least one series of wave groups or periodic amplitude variations for the transmission of telephone conversations, and a combination of high-frequency waves and at least two series of wave groups or periodic amplitude variations for the transmission of telegraph signals, as is hereinafter more fully set forth and described.

In the accompanying figures:

Fig. 1 is a diagrammatic representation of a transmitting station constructed in accordance with the invention and including three different arrangements of telephone and telegraph apparatus;

Fig. 2 shows a modification of part of the transmitting apparatus of Figure 1;

Fig. 3 shows another modification of part of the transmitting apparatus of Figure 1; and

Fig. 4 shows a receiving station on my system, having three different sets of circuits and receiving apparatus.

In Figure 1 the alternating current generator G energizes the field winding F of the high-frequency alternator H, thereby impressing periodic amplitude variations, which should have a frequency above the limits of audibility, upon the current from H. The switch S is used to connect the alternator H with either the telephone transmitter T or the interrupter I and key K, according as it is desired to send telephone or telegraph messages. In the former case, the high-frequency current from H, with the amplitude variations due to the generator G, will have telephonic vibrations superposed upon it by T, and then, by means of the

coupling coils L and L¹, these combined current waves will be impressed upon the antenna A. When it is desired to send telegraph messages, the switch S is connected with the interrupter I and the key K, the frequency of the interrupter being different from, and usually less than, the frequencies of the alternator H and the generator G. Telegraph signals are sent in the usual way by means of the key K, and the combined current wave is impressed upon the antenna A by means of the coupling coils L and L¹.

A second kind of transmitting apparatus is shown in the middle part of the figure where the oscillatory arc O is supplied from a source of direct current N N¹, through the choke coils X and Y. This arc produces oscillations in the circuits O L⁵ L³ C and O L⁴ C¹, the frequencies of these oscillations depending upon the values of the inductances L⁵ and L³ and L⁴, and the capacities C and C¹, respectively. These inductances and capacities are so adjusted that high-frequency oscillations, of the order of hundreds of thousands per second, are produced in the circuit O L⁵ L³ C, and oscillations of a lower frequency, but still above the limits of audibility, are produced in the circuit O L⁴ C¹. These oscillations in O L⁴ C¹ produce periodic variations of amplitude in the oscillations of circuit O L⁵ L³ C. Inductively coupled to the circuit O L⁵ L³ C by means of the coils L⁵ and L³, is the circuit containing the switch S¹, this switch being so adjustable as to connect either the telephone transmitter T¹ or the interrupter I¹ and key K¹ with the coil L⁵, so that either telephone vibrations or telegraph signals can be impressed upon the circuit O L⁵ L³ C, and thence, by means of the coupling coils L³ and L², upon the antenna A. The frequency of the interrupter I¹ should be lower than the frequencies of the oscillatory arc circuits.

A third way of producing periodic amplitude variations in the transmitted waves is shown in the lower part of the figure, where a motor M rotates the coil L⁸ so as to vary its mutual inductance with coil L⁷, and so cause periodic amplitude variations in the high-frequency current induced in the coil L⁷ by the alternator H¹. In circuit with the alternator H¹ and the coil L⁷ is the switch S², which can connect in the circuit either the telephone transmitter T² or the interrupter I² and the key K². The coil L¹

should be rotated at such a speed as to produce amplitude variations of a frequency above the limits of audibility, and the rotation of L^8 affects only its mutual relations with coil L^7 , and does not change its relation to the antenna A and the coils L^2 and L^1 .

In Figure 2, the switch S and key K , or the switch S^2 and key K^2 of Figure 1 are replaced by the key K^3 . In its normal position key K^3 makes contact at U and so completes the circuit from the alternator H^2 through the telephone transmitter T^3 and coupling coil L^9 . In this position of the key K^3 , the circuit is ready for telephone messages. When it is desired to telegraph, key K^3 is operated in the usual way. Contact at U is first broken, thus throwing the telephone T^3 out of circuit, and contact is made at V , thus completing the circuit through the interrupter I^3 .

In Figure 3, the switch S^1 and key K^1 of Figure 1 are replaced in a similar manner by key K^4 . In its normal position the key K^4 makes contact at U^1 and completes the circuit from the battery J^1 through the telephone transmitter T^4 and the coil L^{10} . When the battery J^1 is used, this auxiliary circuit should be in inductive relation to the circuit supplying the arc O , so that, for instance, the coil L^{10} is inductively coupled with the coil X . When the apparatus shown in Figure 3 is used in inductive relation to the circuit O L^5 L^8 C , of Figure 1, the battery J^1 can be omitted. For telegraphing, the key K^4 is operated in the usual way, first breaking contact at U^1 and then making contact at V^1 and so closing the circuit through the interrupter I^4 .

In all these arrangements of apparatus it will be seen that when telephoning is to be carried on, periodic amplitude variations, of a frequency above the limits of audibility, are impressed upon the high-frequency waves, and that when it is desired to telegraph, there is added an interrupter, which breaks up the waves into groups or sets, the set frequency being of a lower order than either the frequency of the amplitude variations or that of the high-frequency waves.

In Figure 4 there is shown a receiving station with three different sets of receiving circuits, corresponding to the three transmitting sets shown in Figure 1. The antenna B has three tuned circuits, B L^{11} C^2 E^1 , B L^{19} C^6 E^1 and B L^{27} C^{10} E^1 . The circuit B L^{11} C^2 E^1 , containing the coil L^{11} and the variable condenser C^2 , is in resonance with the high-frequency alternator H , of Figure 1, and also with the circuit L^{12} C^3 , with which it is inductively connected by means of the coils L^{11} and L^{12} . The rectifier R^1 and the stopping condenser D permit unidirectional current impulses of the frequency of the variations in wave amplitude caused by the generator G of Figure 1 to

pass through coil L^{13} , and when circuit L^{14} C^4 P L^{15} is in resonance with this latter frequency, currents will be induced in it by means of the coils L^{13} and L^{14} , and telephone conversation from the transmitter T of Figure 1 can be heard at telephone receiver P . When the telegraph key K and interrupter I of Figure 1 are working, unidirectional current impulses will be induced in the untuned circuit L^{16} R^2 L^{17} by means of the coupling coil L^{16} , and the rectifier R^2 will cause current impulses of the frequency of the interrupter I to be impressed upon the circuit L^{18} C^5 P^1 , which is tuned to the frequency of the interrupter I , and telegraph signals will be received in the telephone P^1 .

The other two receiving sets of Figure 4 operate in a similar manner, and need not be explained in detail. In a second receiving set, L^{20} , L^{21} , L^{22} , L^{23} , L^{24} , L^{25} and L^{26} are inductance coils, C^7 , C^8 and C^9 are variable condensers, D^3 is a stopping condenser, R^3 and R^4 are rectifying detectors and P^2 and P^3 are telephone receivers. The circuits of this receiving set are tuned so that it will be operated by a second transmitting set, say the one including the arc O , the key K' and the telephone transmitter T' . In a third receiving set, L^{28} , L^{29} , L^{30} , L^{31} , L^{32} , L^{33} and L^{34} are inductance coils, C^{11} , C^{12} and C^{13} are variable condensers, D^2 is a stopping condenser, R^5 and R^6 are rectifying detectors, and P^4 and P^5 are telephone receivers. The circuits of this receiving set are tuned so that it will respond to a third transmitting set, say the one including the generator H' , the key K^2 and the telephone transmitter T^2 . By means of the apparatus here shown, three telephone conversations can be carried on simultaneously, or three telegraph messages can be sent, or any combination of three telephone and telegraph messages. The circuits of each receiving set are in tune with the wave frequency, the amplitude variation frequency and the wave group frequency of the corresponding transmitting set. The three characteristic frequencies of each transmitting and receiving set may all be different from the characteristic frequencies of the other sets, or only one or two characteristic frequencies may be different, the other frequency being the same for two or more sets. Thus, the same wave length might be used for all three sets, and selectivity secured by having different rates of amplitude variation and wave-group frequency.

A higher degree of selectivity could be secured by introducing an additional amplitude variation or wave-group frequency in each set by means of an additional interrupter or in some other appropriate way, and it is also evident that, while three sets of apparatus are shown in this application, my invention is not confined to three sets,

but that two, four, or any number of sets of apparatus may be employed. In this application there are shown three different varieties of transmitting apparatus, but it is 5 evident that the three sets might be the same, or that two sets might be the same and the third different. My invention, moreover, is not confined to the particular transmitting and receiving apparatus here 10 shown, nor to systems designed for the simultaneous transmission and reception of a plurality of telephone or telegraph messages, since the methods and apparatus defined in many of the appended claims can 15 be utilized in systems designed for the transmission and reception of a single message at a time.

What I claim as my invention and desire to secure by U. S. Letters Patent is:

20 1. A method of multiplex radio telephony which consists in impressing telephonic vibrations upon a plurality of electric waves having different lengths and different amplitude variations, radiating said waves 25 from an antenna, and receiving them upon circuits tuned to the respective wave lengths and amplitude variation frequencies.

20 2. A method of radio telephony which consists in impressing telephonic vibrations 30 upon a combination of electric waves and electric wave groups, radiating said waves and wave groups from an antenna, and receiving them upon circuits tuned to wave lengths and group frequency.

35 3. A method of multiplex radio telephony which consists in generating high-frequency electric waves, impressing upon said waves periodic amplitude variations having a frequency above the limits of audibility but 40 different from the frequency of said waves, superposing telephonic vibrations upon said waves and said amplitude variations, radiating said waves from an antenna, and receiving them upon circuits tuned to the respective wave frequencies and amplitude 45 variation frequencies.

40 4. A method of multiplex radio telephony which consists in transmitting telephonic vibrations by means of a plurality of electric 50 waves in a plurality of series of groups, and receiving said vibrations on telephone receivers connected with circuits tuned to wave lengths and group frequencies.

55 5. In a system of multiplex radio telephony, means for transmitting waves having different lengths in sets said waves having amplitude variations of different frequencies, said amplitude variations being independent of the telephonic vibrations.

60 6. In a system of selective radio telephony, means for generating high-frequency electric waves and for impressing upon said waves amplitude variations having frequencies above the limits of audibility, means 65 for superposing telephonic vibrations upon

said waves and said amplitude variations, and a plurality of receiving circuits tuned to wave length and to amplitude variation frequency.

7. In a system of telegraphy and telephony, transmitting means comprising a source of high frequency electric waves, means operative either to impress telephonic vibrations on said waves, or to interrupt said waves to form telegraphic signals, and 75 a transmitting element arranged to be energized by said last mentioned means to emit either telegraphic or telephonic messages.

8. In a system of telegraphy and telephony transmitting means comprising a source of high frequency electric waves, means operative either to impress telephonic vibrations on said waves, or to form said waves into sets at a given set frequency 85 and to interrupt said sets of waves to form telegraphic signals, and a transmitting element arranged to be energized by said last mentioned means to emit either telegraphic or telephonic messages. 90

9. In a system of telegraphy and telephony, transmitting means comprising a source of high frequency electric waves, means for forming said waves into groups having a given group frequency, means operative either to impress telephonic vibrations on said groups or to divide said groups into sets and to interrupt said sets to form telegraphic signals, and a transmitting element arranged to be energized by said last 100 mentioned means to emit either telephonic or telegraphic messages. 95

10. In a system of telegraphy and telephony, transmitting means comprising a source of high frequency electric waves, 105 means for forming said waves into groups having a given group frequency above the limits of audibility, means operative either to impress telephonic vibrations on said groups or to divide said groups into sets and to interrupt said sets to form telegraphic signals, 110 and an antenna arranged to be energized by said last mentioned means to emit either telephonic or telegraphic messages. 110

11. A method of radio signalling which consists in generating a series of electrical oscillations having a predetermined frequency, producing in said oscillations periodic variations having a frequency different from said first mentioned frequency 115 and above the wave frequency of a tone of maximum audibility at a fixed amplitude, causing said oscillations thus varied to produce corresponding radiant oscillations, receiving said radiant oscillations upon cooperating receiving elements tuned to said frequencies respectively, and producing from time to time further variations in said electrical oscillations in order to form signals. 120

12. A method of radio signalling which 130

consists in generating a series of electrical oscillations having a predetermined frequency, producing in said oscillations periodic variations having a frequency different from said first mentioned frequency and above audibility, causing said oscillations thus varied to produce corresponding radiant oscillations, receiving said radiant oscillations upon cooperating receiving elements tuned to said frequencies respectively, and producing from time to time further variations in said electrical oscillations in order to form signals.

13. A method of radio signalling which consists in generating a series of electrical oscillations having a predetermined frequency, producing in said oscillations periodic amplitude variations having a frequency different from said first mentioned frequency and above the wave frequency of a tone of maximum audibility at a fixed amplitude, causing said oscillations thus varied to produce corresponding radiant oscillations, receiving said radiant oscillations upon cooperating receiving elements tuned to said frequencies respectively, and producing from time to time further variations in said electrical oscillations in order to form signals.

14. A method of radio signalling which consists in generating a series of electrical oscillations having a predetermined frequency, producing in said oscillations periodic amplitude variations having a frequency different from said first mentioned frequency and above audibility, causing said oscillations thus varied to produce corresponding radiant oscillations, receiving said radiant oscillations upon cooperating receiving elements tuned to said frequencies respectively, and producing from time to time further variations in said electrical oscillations in order to form signals.

15. In a system of signaling, means for generating a series of high frequency electric waves and for impressing upon said waves periodic variations having a frequency above audibility, means for modifying said waves and said periodic variations from time to time to form signals, and means for receiving said signals comprising a plurality of receiving elements tuned to the frequency of said waves and the frequency of said variations respectively.

16. In a system of signaling, means for generating a series of high frequency electric waves and for impressing upon said waves periodic amplitude variations having a frequency above the upper limits of audibility, means for modifying said waves and said periodic amplitude variations from time to time to form signals, and means for receiving said signals comprising a plurality of receiving elements tuned to the frequency

of said waves and the frequency of said amplitude variations respectively.

17. In a system of wave transmission, the combination with a circuit of means cooperating therewith for causing said circuit to transmit a plurality of series of high frequency waves, of means for periodically varying the amplitude of the waves in each series, and means operative either to form the waves of each series into sets of groups of waves or to impress telephonic vibrations on each series.

18. A system comprising means for generating periodic impulses having a predetermined frequency and for producing in said impulses either simultaneously or selectively a plurality of series of periodic variations having different predetermined frequencies respectively, each of said last mentioned frequencies being different from said first mentioned frequency, and means for receiving said impulses and variations including a circuit tuned to respond to impulses of said first mentioned frequency, detecting means controlled by said circuit, a plurality of oscillatory circuits controlled by said detecting means and tuned respectively to said second mentioned frequencies, and a plurality of detectors controlled by said last mentioned circuits respectively.

19. A method of radio signaling which consists in generating a series of electrical oscillations having a predetermined frequency, producing in said oscillations periodic variations having a frequency different from said first mentioned frequency and substantially above audibility, causing said oscillations thus varied to produce corresponding radiant oscillations, receiving said radiant oscillations upon cooperating receiving elements tuned to said frequencies respectively, and producing from time to time further variations in said electrical oscillations in order to form signals.

20. A method of radio telephony which consists in generating high frequency electric waves, impressing upon said waves periodic variations having a frequency above the limits of audibility and different from the frequency of said waves, superposing telephonic vibrations upon said waves and variations, radiating said waves from an antenna, and receiving said radiated waves upon cooperating circuits tuned to the frequency of said waves and to the frequency of said variations respectively.

21. In a system of radio telephony, means for generating a series of high frequency electric waves and for impressing upon said waves periodic variations having a frequency above the upper limits of audibility, means for modifying said waves and said periodic variations from time to time to

form signals, and means for receiving said signals comprising a plurality of receiving elements tuned to the frequency of said waves and the frequency of said variations respectively.

22. A carrier wave transmission system comprising means for receiving and detecting the energy of a series of waves modulated at a plurality of frequencies and thereby producing a current having frequency components corresponding to said first mentioned frequencies, means for selecting one of said components of said current, and means controlled by said second mentioned means for producing a current having a dominating frequency less than that of said selected component and corresponding to one of said first mentioned frequencies.

23. The combination with means for receiving the energy of a series of impulses modulated at a plurality of frequencies, of means arranged to be controlled by the received energy for producing a current of electrical impulses having a frequency corresponding to one of said first mentioned frequencies and means arranged to be controlled by said current of electrical impulses for producing a current of electrical impulses having a frequency corresponding to another of said first mentioned frequencies.

24. The combination with a transmission system including means for transmitting a series of waves modulated at a plurality of frequencies, of a receiving system including means for receiving the energy of said modulated waves and means controlled by said receiving means for producing as a result of the action of said energy, a current of electrical impulses having a frequency corresponding to one of said first mentioned frequencies, and means arranged to be controlled by said current of electrical impulses for producing a current of electrical impulses having a frequency corresponding to another of said first mentioned frequencies.

25. The combination with means for transmitting impulses having an inaudible frequency modulated at a substantially inaudible second frequency and also at an audible frequency, of means for receiving the energy of said impulses thus modulated, demodulating means controlled by said received energy for producing a current of electrical impulses having a frequency corresponding to said second mentioned frequency, and means arranged to be controlled by said last mentioned impulses for producing a current of electric impulses having a frequency corresponding to said audible frequency.

26. A system of signalling comprising means for producing impulses including two series of impulses having different sub-

stantially inaudible frequencies respectively in combination with receiving means responsive to said impulses, and receiving means controlled by said first mentioned receiving means and tuned to respond to the lower one of said two series of impulses.

27. In a selective system of transmission of electric waves, a transmitter comprising means for radiating high frequency electric waves, and for producing in said high frequency electric waves a periodically recurring variation of the emitted energy, the period of said variation of energy being independent of the high frequency oscillations of the said wave, and a receiving station containing a circuit energized by said independent energy variation of the transmitter, said circuit having a period uninterferable by said high frequency oscillations or oscillations of audible frequency.

28. In a selective system for the transmission of electroradiant energy, the combination with transmission means arranged to emit electroradiant oscillations of a predetermined high frequency, and to impress on said oscillations a plurality of series of periodic variations of different predetermined frequencies, of receiving means arranged to selectively receive said oscillations and said variations and to function through the conjoint action of said oscillations and said plurality of series of variations.

29. A system in accordance with claim 28, in which the receiving means functions through the conjoint and successive action of the said oscillations and said plurality of series of variations.

30. In a selective system for the transmission of electroradiant energy, the combination with transmission means arranged to emit a series of sets of groups of electroradiant oscillations of a predetermined high frequency having a predetermined set frequency and a predetermined group frequency, of receiving means arranged to selectively receive said oscillations and to function through the conjoint action of said oscillations, said groups and said sets.

31. A system in accordance with claim 30 in which the receiving means functions through the conjoint and successive action of the said oscillations, said groups and said sets.

32. The method of transmitting and receiving radiant energy which consists in emitting sets of groups of electroradiant oscillations having a predetermined set frequency, a predetermined group frequency and a predetermined wave frequency or oscillation frequency, and selectively receiving said sets of groups of oscillations, and causing the performance of a function as a result of the conjoint action of said oscillations, said groups and said sets.

33. A method in accordance with claim 32, in which the performance of the function is caused as a result of the conjoint and successive action of the said oscillations, said 5 groups and said sets.
34. The method of transmitting and receiving radiant energy, which consists in generating high frequency radiant oscillations having a frequency above audibility 10 and impressing upon said oscillations two series of periodic variations, one of said series having a frequency above audibility and the other of said series having a frequency within the limits of audibility, and causing 15 the functioning of a receiving device as the result of the conjoint and successive action of said oscillations and said periodic variations.
35. A system for transmitting and receiving 20 radiant energy, comprising means for emitting a series of electroradiant impulses having a frequency substantially above audibility, and having impressed therein a series of periodic modifications having a frequency different from said first-mentioned 25 frequency and substantially above audibility, in combination with means for receiving said impulses and modifications including two elements tuned to respond selectively to 30 said impulses and modifications respectively and a receiving device arranged to be controlled by the conjoint action of said elements.
36. A system in accordance with claim 35 35 in which one of said elements is in the form of an electrically tuned circuit.
37. A system in accordance with claim 35, in which each of said elements is in the form of an electrically tuned circuit.
38. A system in accordance with claim 35, 40 in which said elements are arranged to act successively.
39. A system in accordance with claim 35, in which said receiving device is tuned to an 45 audible frequency.
40. A system in accordance with claim 35, in which said receiving device is in the form 50 of a circuit tuned to respond to electrical impulses of a frequency different from either of said first-mentioned frequencies.
41. A system in accordance with claim 35, in which said elements are arranged to act 55 successively and said receiving device is tuned to respond to electrical impulses of a frequency different from either of said first-mentioned frequencies.
42. A system in accordance with claim 35, in which said elements are arranged to act 60 successively and said receiving device is tuned to respond to impulses of an audible frequency.
43. A selective system of wave transmission and reception comprising means for transmitting waves having a predetermined 65 frequency, means for impressing in said waves a plurality of series of periodic variations having different frequencies respectively, and means for selectively receiving said waves and variations including a plurality of cooperating elements tuned to the 70 frequency of said waves and the frequencies of a plurality of said variations respectively, said elements being arranged to act successively.
44. A system in accordance with claim 43, 75 in which each of said elements is in the form of an electrically tuned circuit.
45. A selective system of wave transmission and reception, including means for transmitting waves having a frequency above 80 audibility, means for impressing in said waves two series of periodic variations, one of said series of variations having a frequency above audibility and the other of said series of variations having a frequency 85 within audibility, and means for receiving said waves and variations including two cooperating elements tuned to said two first-mentioned frequencies respectively and a third element controlled by said first-mentioned elements and tuned to said third-mentioned frequency respectively.
46. The method of transmitting and receiving energy, which consists in transmitting a series of waves having a frequency 90 substantially above audibility, impressing in said waves a series of periodic modifications having a frequency different from said first-mentioned frequency and substantially above audibility, selectively receiving said waves 95 and variations, and controlling a receiving device as the result of the conjoint action of said waves and variations.
47. A method in accordance with claim 46, and in which the receiving device is controlled 100 as a result of the conjoint and successive action of said waves and variations.
48. A system for transmitting and receiving energy comprising means for generating a series of periodic impulses having a frequency substantially outside of the range of 105 audibility and for impressing upon said impulses a series of periodic variations having a frequency different from said first-mentioned frequency but substantially outside 110 of the range of audibility, in combination with means for receiving said impulses and variations including two elements tuned to respond selectively to said impulses and variations respectively, and a receiving device 115 arranged to be controlled by the conjoint action of said elements.
49. A system in accordance with claim 48, in which the receiving device is controlled 120 by the conjoint and successive action of said element.
50. A system for transmitting and receiving radiant energy comprising means for transmitting radiant energy in a plurality of 125 series of periodic impulses of different radio 130 frequencies.

5 frequencies, and means for receiving the radiant energy comprising circuits tuned respectively to said series of impulses and arranged to cause current to be supplied to one of said circuits in response to the setting up of current of a predetermined character in another of said circuits.

10 51. A system for transmitting and receiving radiant energy comprising means for transmitting radiant energy in a plurality of series of periodic impulses of different radio frequencies, and means for receiving the radiant energy comprising circuits tuned respectively to said series of impulses and arranged to cause current to be supplied to one of said circuits tuned to a lower frequency in response to the setting up of current of a predetermined character in another of said circuits tuned to a higher frequency.

15 52. A system for transmitting and receiving radiant energy comprising means for transmitting radiant energy in a plurality of series of periodic impulses of different radio frequencies, and means for receiving the radiant energy comprising a single antenna and a plurality of circuits tuned respectively to said series of impulses and connected in cascade arrangement with the antenna.

20 53. A system for transmitting and receiving radiant energy comprising means for transmitting radiant energy in a plurality of series of periodic impulses of different radio frequencies, and means for receiving the radiant energy comprising a plurality of circuits tuned respectively to said series of impulses and connected in cascade arrangement so that current is supplied to each succeeding circuit in response to the setting up of current of a predetermined character in the preceding circuit.

25 54. A system for transmitting and receiving radiant energy comprising means for transmitting radiant energy in a plurality of series of periodic impulses of different radio frequencies, and means for receiving the radiant energy comprising a plurality of circuits connected in series and tuned respectively to said series of impulses, rectifying means intermediate between certain of the adjacent circuits, and a device controlled by the conjoint action of the impulses impressed upon said circuits.

30 55. A method of transmitting and receiving radiant energy which consists in transmitting radiant energy as a plurality of series of periodic impulses of different radio frequencies, selectively receiving said impulses with rectification of one of said series to bring out impulses of another of said series, and controlling a receiving device as a result of the conjoint action of the impulses.

35 56. A system of signaling including means for generating electrical waves having a

fixed frequency characteristic and variable speech frequency characteristic, an indicating device responsive to the speech frequency characteristic of said waves, means for impressing upon said waves an additional fixed frequency characteristic to which said indicating device is unresponsive, and an element co-acting with the indicating device and tuned to the frequency of said additional fixed characteristic so as to increase the selectivity with which the speech signals may be received.

40 57. A system of signaling including means for generating electric waves having a fixed radio frequency characteristic and a variable speech frequency characteristic, an indicating device responsive to the speech frequency characteristic of said waves, means for impressing upon said waves a different fixed frequency characteristic to which said indicating device is unresponsive, and a circuit co-acting with the indicating device and tuned to the frequency of said different fixed characteristic so as to increase the selectivity with which the speech signals may be received.

45 58. A system of signaling including means responsive to electric waves having a predetermined high frequency, means for impressing speech frequency variations upon said waves, an indicating device responsive to said speech frequency variations, means for impressing upon said waves additional frequency variations differing both from the first-mentioned frequency and from the speech frequency variations, said indicating device being unresponsive to said additional variations, and an element co-acting with the indicating device and tuned to the frequency of said additional variations so as to increase the selectivity with which the speech signals may be received.

50 59. A system of signaling including means for generating electrical oscillations having a predetermined frequency, means for impressing speech frequency variations upon said oscillations, an indicating device responsive to said speech frequency variations, means for impressing upon said oscillations periodic amplitude variations having a frequency intermediate the frequency of said oscillations and said speech frequency variations, and a circuit co-acting with the indicating device and electrically tuned to the frequency of said periodic amplitude variations so as to increase the selectivity with which the speech signals may be received.

55 60. The combination in a wireless signaling system of means for transmitting a single series of signals by waves of two different radio frequencies simultaneously radiated from an antenna, and a receiving station having means for receiving the waves, means for producing from them a current having a frequency less than the higher of

- 5 said two different radio frequencies and determined by said radio frequency waves, said last-mentioned current being above audibility, an oscillating circuit resonant to said 5 last-mentioned current, and means cooperating with the oscillating circuit for detecting the signals.
61. The combination in a wireless signaling system of means at a transmitting station for producing radio frequency currents having definite amplitude pulsations of a frequency above audibility, a receiving station having means for receiving signals transmitted by the currents thus produced at 10 the transmitting station, means for changing the radio frequency currents received by this antenna to an alternating current of a frequency corresponding to the amplitude pulsations of the currents produced at the transmitting station, and means for the selective reception and detection of this current.
62. The combination in a wireless signaling system of transmitting apparatus comprising a source of energy of radio frequency including a second controlling source of energy of substantially lower frequency but above audibility for controlling the flow of current from the radio frequency source so 15 as to produce amplitude pulsations therein of a frequency equal to that of the controlling source, means for transmitting waves of two different radio frequencies derived from the current having amplitude pulsations, means for impressing a single series of signals on said waves, means at a receiving station for receiving the waves of two radio frequencies and producing from them an alternating current of a frequency correspond- 20 ing to the frequency of the controlling source in the sending station, and means for the selective reception and detection of the current thus produced.
63. A receiving system for waves comprising a plurality of successively responsive circuits connected together in cascade relation and tuned respectively to a plurality of wave group frequencies, and a device arranged to be actuated in response to 25 the conjoint action of a plurality of said circuits.
64. In a system of wave transmission, the combination with means for transmitting a plurality of series of groups of waves of different group frequencies, of receiving means comprising a plurality of cooperating elements, connected together in cascade relation and tuned to said frequencies respectively, and a device arranged to be actuated in response to the combined action of 30 a plurality of said elements.
65. The combination with means for transmitting waves having a predetermined high frequency, of means for impressing on said waves a series of periodic amplitude 35 variations having a frequency less than said first-mentioned frequency, means for dividing said waves into groups or sets having a frequency less than the frequency of said amplitude variations, and means for receiving said waves including three elements tuned to respond to said three frequencies respectively, and a receiving device arranged to be controlled by the conjoint action of said elements.
66. A method of wave transmission, which consists in transmitting a series of electroradiant waves having a predetermined high frequency above the limits of audibility, impressing upon said waves a plurality of series of periodic variations having different predetermined frequencies, one of said series of variations having a frequency less than said first-mentioned frequency but above the limits of audibility, 40 and other of said series of variations having a frequency within the limits of audibility, receiving said waves on a plurality of co-operating elements tuned to respond selectively to said first-mentioned frequency and 45 to said second-mentioned frequencies, and controlling a receiving device as a result of the conjoint action of said elements.
67. In a radio transmission system, the combination with means for producing continuous radiant impulses of a predetermined frequency of means separate from said producing means and operative to impress upon said impulses a series of periodic variations having a frequency different from said first-mentioned frequency, and means automatically operative to interrupt said impulses periodically at a frequency different 50 from said first-mentioned frequencies.
68. A system of radio signaling which comprises a source of high frequency oscillatory energy, means for transmitting said oscillatory energy, a receiver for said energy, means for producing current at the receiver having a predetermined frequency 55 above audibility but lower than the frequency of said oscillatory energy, said last-mentioned means including a source of high frequency energy arranged to cause its energy to be combined with said high frequency oscillatory energy, means for detecting said current, and means for indicating the current.
69. A method for securing selectivity in electric wave transmission which consists in transmitting waves of different definite wave lengths in groups at different definite group frequencies and transmitting the wave groups in sets at different definite set rates.
70. In a selective signaling system, a receiving circuit tuned to the wave frequency of a high frequency signal wave having a low frequency component, a second circuit tuned to an intermediate frequency above 60

- audibility and connected in cascade relation with said first-mentioned circuit, means for producing current of said intermediate frequency, said means including a detector interposed between said circuits and a source of electrical oscillations arranged to combine its energy with the energy of the signal wave, and an indicator associated with said second circuit. 65
6. 71. A multiplex transmission system for radiant energy, comprising means for emitting a series of radiant oscillations having a predetermined frequency, a plurality of separately operative devices for impressing on said oscillations a plurality of series of periodic modifications having different predetermined frequencies respectively, and means included in each of a plurality of said devices for impressing a separate series of 70 variations corresponding to sound waves on said oscillations in connection with each of a plurality of said series of modifications. 75
72. In a selective signaling system, a receiving circuit tuned to the wave frequency of a high frequency signal wave having a fixed wave frequency characteristic and a variable speech frequency characteristic, an indicating device responsive to the speech frequency characteristic of said waves, means for impressing upon said waves an additional fixed frequency characteristic to which said indicating device is unresponsive, said means including a source of electrical 80 oscillations arranged to combine its energy with that of the signal wave, and a circuit co-acting with the indicating device and conductive only to currents of the frequency of said additional fixed characteristic. 85
73. In a selective signaling system, a receiving circuit tuned to the wave frequency of a high frequency signal wave having a fixed wave frequency characteristic and a variable speech frequency characteristic, an indicating device responsive to the speech frequency characteristic of said waves, a second circuit tuned to a predetermined frequency above audibility but lower than the frequency of the signal wave and connected 90 in cascade relation with said first-mentioned circuit and with said indicating device, and means for producing current of said last-mentioned frequency in said second circuit under the control of the signal wave, said means including a detector interposed between said circuits and a source of electrical oscillations arranged to combine its energy with the energy of the signal wave. 95
74. In a selective signaling system, a receiving circuit tuned to the wave frequency of a high frequency signal wave, a second circuit tuned to a predetermined frequency above audibility but lower than the frequency of the signal wave and connected in 100 cascade relation with said first-mentioned circuit, means for producing current of said last-mentioned frequency, said means including a detector interposed between said circuits and a source of electrical oscillations arranged to combine its energy with the energy of the signal wave, and an indicator associated with said second circuit. 105
75. In a selective signaling system, a receiver for oscillatory energy, means for producing current at the receiver having a predetermined frequency above audibility but lower than the frequency of said oscillatory energy, said last-mentioned means including a source of high frequency energy arranged to cause its energy to be combined with said high frequency oscillatory energy, a circuit tuned to the frequency of said current, and means for detecting said current. 110
76. In a system of telegraphy and telephony, means responsive to electrical energy in the form of high frequency waves having a low frequency component, means including a source of electrical oscillations of superaudible frequency for producing in connection with said high frequency waves an additional component differing in frequency both from the first named frequency and from the frequency of said low frequency component, a tuned circuit adjusted to respond to said differing frequency, a detector controlled by said circuit element, and an indicating device operable only by the joint action of said high frequency waves and said additional component of differing frequency, said indicating device being unresponsive to said differing frequency. 115
77. In a system of telephony, means selectively responsive to high frequency electrical oscillations having telephonic vibrations superposed thereon, means for producing in connection with said oscillations additional frequency variations differing both from the high frequency oscillations and from the telephonic vibrations, means tuned to respond only to said additional frequency variations, a detector controlled by said tuned means, and an indicating device controlled by said detector. 120
78. In a system of telephony, means selectively responsive to high frequency electrical oscillations having telephonic vibrations superposed thereon, means for producing in connection with said oscillations additional frequency variations differing from the high frequency oscillations and above audibility, a detector, an indicating device controlled by said detector, and means for impressing on the input of said detector only currents of substantially said additional frequency. 125
79. In a system of communication utilizing a signal wave comprising high frequency electrical oscillations having variations cor-

responding to signals superposed thereon, means including a source of energy for forming said waves into groups having a given group frequency above the limits of 5 audibility, a detector for said high frequency waves, a detector for said group of waves, a circuit interposed between said detectors and conductive only to currents of the frequency of said groups, and a signal indicating device controlled by said last named detector.

This specification signed and witnessed this 9th day of May A. D., 1912.
